UNITED STATES PATENT OFFICE.

WILLIAM S. WELLS, OF BETHLEHEM, PENNSYLVANIA, ASSIGNOR TO BENJAMIN EAST-
WOOD COMPANY, OF PATERSON, NEW JERSEY, A CORPORATION OF NEW JERSEY.

SHUTTLE-BOX MECHANISM.

Original application filed April 2, 1923, Serial No. 629,274. Divided and this application filed July 7, 1924. Serial No. 724,597.

This invention relates to looms and in particular to so-called box-looms, that is, looms in which a plurality of shuttles are used and they are selectively brought to position for flight across the lay by shifting a container or box structure therefor into proper relation to the lay or batten for such flight of the selected shuttle. In the present adaptation of the improved box-loom 5 two shuttles are employed and they are designed to be called alternately at regular intervals; in short, the loom is of the two-by-one type, i. e., wherein there is a single or fixed box at one end of the lay and a shifting box structure having two cells for the two shuttles at the other end. These details, however, are to be regarded as immaterial.

The present application is a division of 20 my application, Serial No. 629,274, filed April 2, 1923.

The improvements contemplate movement of the boxes transversely of the batten and means for effecting release of each shuttle 25 when it is about to be thrown across the batten or lay.

In the drawings—

Fig. 1 is a side elevation of a loom embodying the invention;

30 Fig. 2 is a plan of the shuttle-boxes;

Fig. 3 is a front elevation thereof; and

Fig. 4 is a sectional view on line 4—4, Fig. 2, one check-lever having been moved to releasing position.

35 The loom shown in Fig. 1 is the type set forth for example, in my application Serial No. 615,988, Patent No. 1,564,386, in which each picking member 1 is impelled so as to throw the shuttle by first cocking it subject to the tension of a spring, as 2, and then releasing it,—as through the medium of a 40 lever 3 for effecting the cocking which is oscillated from a rotary means 4 in gear with the crank-shaft 5 of the loom which, through pitman 6, reciprocates the batten 7, and a lever 8 for effecting the release, also 45 oscillated from means 4. This, however, is immaterial in reference to the present invention.

50 The battens 7 has the picking member 1 movable in a slot 9 (Fig. 4) therein in the way usual in plain looms. That is to say, instead of the wooden beam forming the batten terminating in substantial coincidence

with one side of the loom and being equipped 55 with an extension frame in which the box-structure is to slide, according to the usual construction of box looms, it is left extending and provided with the slot 9 for the picking member, as in plain looms. 60 11 (Fig. 3) is the shuttle race-board, which in the present case is made to terminate near the side frame 12 of the loom.

A plate 13 (Fig. 3) is fixed on the projecting end of the batten and forms the 65 bed on which the box-structure is to slide. Near its inner end it has a transverse groove 14 formed in its top surface; its outer end portion is thickened up and has an overhang 15. The plate also has a slot 16 which 70 registers with the slot 9 of the batten. At its inner end and at front and back it has the upstanding ears 18. At the back two bearing arms 19 project from the plate, the 75 purpose of which will be explained herein-after.

On this plate slides transversely of the batten and horizontally a box structure which may be described as follows: It has a longitudinal central cross-sectionally I- 80 shaped partition 20 whose basal portion 21 forms with the strips 22 the floors of two shuttle boxes, one on each side of the partition, each slot left at 23 being adapted to register with the slot 16 when the box structure is shifted. It has an underneath guiding rib 27 to run in groove 14, and to retain it in place there is a fin 28 engaged under overhang 15 and a plate 29 bridges the upstanding ears 18. There is a transverse 90 housing 30 at the outer end of partition 20 and fixed thereto, being divided by the partition. It will be understood that a shuttle space is formed at each side of the partition. On vertical studs 31 in the housing are 95 fulcrumed the outer ends of stiff inflexible check levers 32, each of which is held by a plate spring 33 pressed inwardly against a thin steel strip 34 forming the outer wall of the box (the inner grooved wall of which is formed by the partition 20); each plate spring is supported at one end by the end of housing 30 and by a pin 35 at the other. The spring, acting through the lever, normally exerts pressure on the strip 34 which 100 coacts normally with the partition to grip a shuttle if present in the box.

As in my mentioned application Serial

No. 615,988, the pressure exerted on each shuttle when entering a box is relieved at the moment it is impelled. The means for effecting this includes a pair of bell-crank levers 36 which are fulcrumed on pins 37 on the shuttle box structure so that the horizontal arm of each projects toward the other lever and the other arm projects down relatively inward of the free end of the check lever 32. The springs 33, acting through levers 32, normally tend to preserve the first-named arms of levers 36 alined. The roller-equipped end of another lever 38, fulcrumed in a bracket 39 on plate 29, is adapted to ride upon the horizontal arms of levers 36 as the box structure is shifted back and forth, and when, upon each such shifting, the shuttle then alined with the batten is to be shot from its box the lever 38 is caused to depress the lever 36 it then overlies to move outward the corresponding check lever and so relieve the pressure on the shuttle. This may be accomplished by the push-rod 39 moving vertically in suitable guiding means 40 on the lay-swords supporting the batten and actuated in any way (as by lever 8) on every other pick of the loom.

A picker 1^a slides on bed-plate 13 over slot 16, being penetrated by the stick 1 in the usual way. At the outer end of the bed-plate is a suitable housing 41 for the picker.

In the arms 19 is fulcrumed a rock-shaft 42 carrying levers 43 connected with ears 44 on the box structure by links 45. A lever 46 on shaft 42 is connected by an adjustable pitman 47 with a lever 48 fulcrumed in the side of the loom frame. By a suitable connection 49 this lever is connected with any suitable dwell-motion mechanism 50 driven by gear 4.

Having thus fully described my invention, what I claim as new and desire to secure by Letters Patent is:—

1. In combination, a batten-including supporting structure having a shuttle race, a set of shuttle boxes movable transversely of the race and having means acting to hold each boxed shuttle in its box, means to move the set of boxes to place one and then anoth-

er box in alinement with the race, means to eject from the box so alined with the race the shuttle present therein, and means to move the first-named means into releasing relation to such shuttle prior to such ejection thereof from the box. 55

2. In combination, a batten-including supporting structure having a shuttle race, a set of shuttle boxes movable transversely of the race, separate means, one for each box, 60 acting to hold the shuttle boxed therein, means to move the set of boxes to place one and then another box in alinement with the race, means to eject from the box so alined with the race the shuttle present therein, 65 and means to cause the corresponding one of the first-named means to release such shuttle prior to such ejection thereof from the box.

3. In combination, a batten-including supporting structure having a shuttle race, a set of shuttle boxes movable transversely of the race and having means acting to hold each boxed shuttle in its box, devices, one for each box, to cause said means to release the shuttles, means to move the set of boxes to place one and then another box in alinement with the race, and means, on each such movement, to cause the device corresponding to the shuttle so alined with the race to 75 cause the first-named means to release such shuttle.

4. In combination, a batten-including supporting structure having a shuttle race, a set of shuttle boxes movable transversely of the race and having means acting to hold each boxed shuttle in its box, devices, one for and movable transversely with each box, to cause said means to release the shuttles, means to move the set of boxes to place one 80 and then another box in alinement with the race, and means, on each such movement and with reference to which said devices are movable with the boxes, to cause the device corresponding to the shuttle so alined with the race to cause the first-named means to release such shuttle. 85

In testimony whereof I affix my signature

WILLIAM S. WELLS.
